G. H. Benjamin

UNITED STATES PATENT OFFICE.

GEORGE HILLARD BENJAMIN, OF NEW YORK, N. Y., ASSIGNOR TO SIEMENS & HALSKE, OF BERLIN, GERMANY.

INCANDESCENT LAMP.

SPECIFICATION forming part of Letters Patent No. 495,240, dated April 11, 1893.

Application filed November 14, 1892. Serial No. 451,991. (No model.)

To all whom it may concern:

Be it known that I, GEORGE HILLARD BENJAMIN, a citizen of the United States, residing in the city, county, and State of New York, have invented new and useful Improvements in Incandescent Lamps, of which the following is a specification.

My invention generally consists in constructing an incandescent electric lamp in such a manner that the part which carries and supports the incandescent filament may be removed from the inclosing globe to permit of the introduction of a new filament when required.

It further consists in the means employed for sealing or uniting the two parts of the lamp so as to form an air-tight globe and yet allow of the separation of the two parts of the lamp when desired.

In the accompanying drawings which illustrate my invention, similar figures of reference indicate like parts.

Figure 1 is a vertical section. Fig. 2 is an elevation of the base piece. Fig. 3 is a vertical section through the base piece. Fig. 4 is a transverse section of the base piece on the line $x-x$ of Fig. 1. Fig. 5 is a vertical section through a portion of the globe and base piece, showing the relation of the two parts when they are joined and the lamp ready for use.

Referring to the figures, 20 represents the inclosing globe or bulb of the lamp. This portion may be given any desired shape and may be either blown, cast or pressed. The lower end, or neck of the globe, 21, is made cylindrical in form and is provided with a groove 22 on its inner surface. Preferably, the lower inner portion of the neck of the globe is ground, or subjected to the action of a sand blast, so as to slightly roughen the surface and bring it to as near the shape of a true cylinder as possible.

23 is the base piece, which is made hollow,—it is round at the top, and provided with a groove 24 on its exterior surface, which corresponds with the groove 22 in the neck of the lamp when the base piece is in position.

It is also provided with a vertical groove 25 and with a flange 26 on its lower surface.

The flange, when the base piece is in place, fits over the lower edge 27 of the neck of the lamp. The exterior surface of the base piece may be ground or treated to the action of a sand blast, so as to slightly roughen its surface.

28 represents a tube carried through the base piece, through which the air contained in the interior of the globe may be exhausted.

29 represents a filament of carbon, or other suitable material for giving light by incandescence, connected to the leading in wires 30, which may be of any suitable material, and properly sealed into the top of the base piece in the usual manner with incandescent lamps, or otherwise fastened therein. Suitable wires (not shown) may be connected to the leading in wires 30 to permit the lamp to be coupled with a source of energy.

By grinding, or treating the inner surface of the neck of the lamp and the outer surface of the base piece as described, I obtain a ground joint which of itself is fairly tight, but not sufficiently so to prevent the ingress of air when the globe has been exhausted.

To seal the base piece into the neck of the lamp, I proceed in the manner which I will now describe: 31 represents a fine wire covered with an insulating material, which is located in the groove 24, crossed and carried down the groove 25, so that its two terminals extend without the base piece, as shown in Fig. 2. Before placing the wire 31 in the grooves 24 and 25, I cover the wire, or fill the grooves with a paste made of a material which, when subjected to heat and subsequently cooled, will become hard and non-porous. Preferably, I use for the purpose a preparation of hydro-carbon,—such as is commonly employed for uniting carbon filaments with the metallic leading in wires of incandescent lamps; that is to say, a thick carbon oil, or a mixture of an oil (such as crude petroleum) and carbon, or I may use a solution of asphaltum, or, in certain cases, I may use an amalgam made up of different materials which, on cooling, will expand. Where a solution of hydro-carbon, or a mixture of oil and carbon is employed, the degree of consistency of the solution can readily be determined by

experiment. Where an amalgam is employed, I may use an alloy composed of lead (nine parts), antimony (two parts), and bismuth (one part); or an amalgam of other materials may be made which will answer a similar purpose. Before inserting the base piece, I may also fill the groove 22 in the neck of the globe with the hydro-carbon solution of the amalgam. After this is done, the outer surface of the base piece is covered with a thin varnish and pushed into position in the neck of the globe, so that the two slots 22 and 24 register. Then I connect the two terminals of the wire 31 with a source of electricity and transmit sufficient current through it to carbonize the insulating material on the wire, also to melt the carbonaceous material or amalgam surrounding the wire. The current transmitted should be sufficient to heat not only the materials mentioned, but also to heat the glass of both the globe and the base piece in the vicinity of the grooves. In the case where a carbonaceous material is used, I continue the current for such a time as to thoroughly carbonize, or render hard, the carbonaceous material. When this has been accomplished, the glass of the globe and neck around the groove is compressed, as shown in Fig. 5, or the grooves may be pressed toward each other from the inner surface of the base piece and the outer surface of the lamp globe. In the case where an amalgam is used, it is only necessary to bring the materials to a melted condition by the action of the current, and then compress the glass. The result of either method of procedure is a perfectly air-tight joint. Where an amalgam is used, it may be formed as a wire and introduced into the groove, in which case it will be unnecessary to employ the wire 31, as the amalgam wire will itself be a conductor of electricity. In case the filament of the lamp should be destroyed by continued use, or in any other manner, and it is desired to introduce a new filament, the terminals of the wire 31 can again be connected to the source of energy and a current be transmitted through the wire. By so doing, the glass in the vicinity of the grooves is heated and the base piece may be removed; after which the grooves can be reformed in the neck of the globe, and a new filament and base piece be inserted and secured in position, as before.

In practice, I find that when either the hydro-carbon solution or the amalgam is employed, these bodies virtually unite with the glass, they come in contact with under the influence of the heat of the current, and that by reason of the pressure exerted, their mass is compacted so that they are impervious to air.

I wish it understood that I do not limit myself to any particular shape of lamp globe, base piece, or grooves, as many changes may be made from the form shown in the drawings, without departing from the intent of my invention.

I claim as my invention—

1. An incandescent lamp comprising a filament, leading in wires, an inclosing chamber composed of two sections, and a wire formed of a metal interposed between said sections. 70
2. An incandescent lamp, comprising a filament, leading in wires, an inclosing chamber composed of two sections, and a wire formed 75 of an alloy of metals located between the two.
3. In an incandescent lamp, the combination of a globe provided with a circumferential groove in the neck thereof, a removable base piece provided with a circumferential 80 groove which registers with the groove in the neck of the lamp, and said base piece also provided with a vertical groove, and a conducting body located in said grooves.
4. In an incandescent lamp, the combination of a globe, provided with a groove 22, 85 and a base piece, provided with grooves 24 and 25, substantially as described.
5. In an incandescent lamp, the combination of an inclosing globe, a removable base 90 piece, a wire surrounding the base piece and having its terminals carried out of the lamp, and material surrounding the wire which, under the action of heat, will unite with the glass of which the globe and base piece are made, 95 substantially as described.
6. In an incandescent lamp, the combination of an inclosing globe, a removable base piece, a wire surrounding the base piece and having its terminals carried out of the lamp, 100 and said wire composed of a material which, under the action of heat, will unite with the glass of which the globe and base piece are made.
7. The method of forming an air-tight seal 105 between two sections of an inclosing glass chamber for an incandescent lamp, which consists in introducing between the two sections a conducting body of a character which, under the action of heat, will unite with the glass, and subjecting said body and the glass in the vicinity thereof to the action of heat locally applied to the conducting body.
8. The method of forming an air-tight seal 115 between two sections of an inclosing glass chamber for an incandescent lamp, which consists in introducing between the two sections a conducting body of a character which, under the action of heat, will unite with the glass, and subjecting said body and the glass 120 in the vicinity thereof to the action of heat locally applied to the conducting body, and finally compressing the glass around said body.
9. The method of forming an air-tight seal 125 between two sections of an inclosing glass chamber for an incandescent lamp, which consists in transmitting an electric current through a conducting body located between the two sections of the inclosing globe, whereby 130 said conducting body and the glass in apposition therewith are raised to a high temperature, and a hermetic seal effected.
10. The method of forming an air-tight seal

between two sections of an inclosing glass chamber for an incandescent lamp, which consists in transmitting an electric current through a conducting body located between the two sections of the inclosing globe, and subsequently pressing the highly heated glass surfaces together and in intimate contact with the conducting body.

In testimony whereof I affix my signature in the presence of two witnesses.

GEORGE HILLARD BENJAMIN.
